BASE FOR SUPPORTING CUSHIONS ON
FURNITURE FRAMES

Albert W. Nemmer, Cheektowago, N. Y.

Application January 20, 1948, Serial No. 3,285

6 Claims. (Cl. 155—178)

1

This invention relates to a base for supporting a cushion on a furniture frame and more particularly to a base which is made of a single piece of sheet metal and supports a resilient or spring cushion in a frame for furniture which is of rectangular form, such as chairs, sofas, settees and the like.

It is the object of this invention to provide a base of this character which is not only simple and durable in construction but also forms a strong and reliable support for the cushion and also serves to rigidly connect the several members of the frame and utilize the material used to make the base to greater advantage without any increase in the cost of production and thereby effecting a substantial economy in manufacture and also producing a superior product.

In the accompanying drawings,

Fig. 1 is a fragmentary perspective view of a piece of furniture showing a base embodying this invention mounted in the frame thereof.

Fig. 2 is a fragmentary sectional perspective view of one corner of this base viewed from the inner side thereof.

Fig. 3 is a similar view looking at the same from the outer side thereof.

Fig. 4 is a front elevation of the furniture frame and the cushion supporting base mounted thereon.

Fig. 5 is a side elevation thereof.

Fig. 6 is a vertical cross section taken on line 6—6, Fig. 5.

Fig. 7 is a vertical longitudinal section taken on line 7—7, Fig. 4.

Figs. 8 and 9 are fragmentary horizontal sections on an enlarged scale, taken on lines 8—8 and 9—9, Fig. 4, respectively.

Fig. 10 is a plan view of a partly formed blank from which the base is constructed.

In the following description similar characters of reference indicate like parts in the several figures of the drawings.

The frame of the furniture upon which the cushioning means are mounted by means of this invention is preferably made of wood in the form of a rectangle and comprises horizontal longitudinal front and rear rails 20, 21 which are spaced from each other, horizontal transverse side rails 22, 23, also spaced from one another, and vertical front and back stumps 24, 25, each of which is connected with the adjacent ends of a longitudinal rail and a transverse rail and forms one of the four corners of the frame. As shown in Figs. 1, 4 and 9, the connection between the rails and the stumps is effected by means of dowels 50

26, but this may be accomplished in any other suitable manner.

The base which supports the spring cushion or other form of cushion in accordance with this invention, is constructed of a single sheet of metal so that its several members are integrally connected and in its preferred form the same is organized and mounted on the frame as follows:

The numeral 27 represents the bottom or bottom plate of the base which is of rectangular form and arranged horizontally within the lower part of the frame.

At its front and rear longitudinal edges this bottom is provided with front and rear vertical walls 28, 29 which project upwardly from the bottom and at its transverse side edges the bottom is also provided with vertical transverse walls 30, 31 which project upwardly from the bottom, the several walls terminating at their upper edges flush with the top of said rails and forming with the bottom a structure having the general shape of a pan or tray.

The front and rear walls of the base are provided, respectively, at their upper edges with 25 hangers forming part of the means for mounting the base on the frame, each of these hangers having the general shape of a hook in cross section and comprising a horizontal longitudinal web 32 projecting outwardly from the respective wall 30 and engaging with the upper side of the respective longitudinal rail, and a flange 33 projecting downwardly from the outer edge of said web and engaging with a rabbet 34 on the upper outer corner of said rail, as shown in Figs. 1, 4 and 7.

Each of the front and rear walls of the base is secured to the inner side of the adjacent longitudinal rail of the frame by fastening means consisting preferably of screws 35, as shown in Figs. 1, 6, 7 and 9.

Each of the transverse side walls 22, 23 of the base is spaced from the adjacent transverse rail of the furniture frame and provided at its upper edge with a reinforcement or stiffening member which comprises a horizontal web 36 projecting outwardly from the respective wall and provided with a vertical flange 37 projecting downwardly from the outer edge of this web, thereby strengthening this wall and preventing distortion of the same when under a load.

At its opposite ends each of the longitudinal walls of the base is provided with attaching lips 38, each of which forms an integral outward extension of the respective wall and is arranged in the same plane and connected with inner side 55 of the adjacent stump by means of screws 39 or

other suitable fastening, as shown in Figs. 6 and 9.

If desired, each attaching lip 38 may be additionally connected with the adjacent part of the furniture frame by a flange 40 projecting laterally inward at an angle from the outer end of the respective lip 38 and connected with the inner side of the adjacent transverse rail of the frame by means of a screw 41, as shown in Fig. 9, or other desired fastening.

At opposite ends of each of the transverse walls 30, 31 the same is provided with outwardly projecting coupling tabs 42, each of which is connected with the inner side of the adjacent lip 38 by spot welding, as shown at 43 in Figs. 2, 3 and 9.

The several members of the base are preferably formed from a single sheet of metal of rectangular outline, as shown in Fig. 10, by providing this blank respectively on its two longitudinal edges with short transverse slits 44 adjacent to the corners of the sheet, also providing the transverse edges of the same with short longitudinal slits 45 adjacent to the corners of the sheet, and also providing the transverse end portions of the sheet with outwardly off-set slits 46, each of which forms an inward extension of one of the longitudinal slits 45.

After the blank sheet has been thus cut, the front and rear longitudinal edge portions are bent upwardly along the lines 47 to form the front and rear walls 28, 29 and the lips 38, and the transverse edge portions of the blank are bent upwardly along the lines 48 to form the transverse walls 30, 31. The front and rear longitudinal edge portions of the blank are also bent along the lines 49, 50 to form the front and rear supporting hooks of the base, and the transverse edge portions of the blank are bent along the lines 51, 52 to form the reinforcing members of the base. The end portions of the lips 38 are bent along the lines 53 to form the flanges 40, and the end portions of the walls 30, 31 are bent along the lines 53 to form the flanges 40, and the end portions of the walls 30, 31 are bent along the lines 54 to form the tabs 42.

In this manner all the material of the blank is usefully employed to produce a strong and efficient base for supporting the cushioning of furniture at relatively low fabricating cost and without waste of material. Moreover, this invention not only forms a stronger connection between the base and the furniture frame but it also firmly and rigidly connects the rails and stumps at each corner of the frame so as to reliably hold them together and thus strengthen the furniture as a whole.

I claim:

1. An integral sheet metal base for supporting a cushion on a furniture frame having front, rear and side rails and stumps at the corners between said rails, said base comprising a horizontal bottom, vertical front, rear and side walls projecting upwardly from the corresponding edges of said bottom, and two of said walls being mounted on the adjacent rails and each provided at its opposite ends with lips extending in the same plane therefrom and connected with the adjacent stumps.

2. An integral sheet metal base for supporting a cushion on a furniture frame having front, rear and side rails and stumps at the corners between said rails, said base comprising a horizontal bottom, vertical front, rear and side walls projecting upwardly from the corresponding edges of said bottom, and two of said walls being mounted on the adjacent rails and each provided

at its opposite ends with lips extending in the same plane therefrom and connected with the adjacent stumps, and coupling tabs arranged at opposite ends of each of the other two walls and each tab projecting laterally outward from the respective wall and connected with the adjacent lip.

3. An integral sheet metal base for supporting a cushion on a furniture frame having front, rear and side rails and stumps at the corners between said rails, said base comprising a horizontal bottom, vertical front, rear and side walls projecting upwardly from the corresponding edges of said bottom, and two of said walls being mounted on the adjacent rails and each provided at its opposite ends with extensions, each of which forms a lip arranged in the same plane as the respective wall and connected with the adjacent stump and a flange arranged on the outer end of the respective lip and projecting at an angle therefrom and connected with the adjacent frame rail.

4. An integral sheet metal base for supporting a cushion on a furniture frame having front, rear and side rails and stumps at the corners between said rails, said base comprising a horizontal bottom, vertical front, rear and side walls projecting upwardly from the corresponding edges of said bottom, and two of said walls being mounted on the adjacent rails and each provided at its opposite ends with lips extending in the same plane therefrom and connected with the adjacent stumps, and coupling tabs arranged at opposite ends of each of the other two walls and each tab projecting laterally outward from the respective wall and connected with the adjacent lip and formed by metal removed from the respective lip to which it is connected.

5. A sheet metal base for supporting a cushion on a furniture frame having a front rail, a back rail, side rails and front and rear stumps at the corners between said rails, comprising a horizontal bottom plate, vertical front, back and side walls projecting upwardly from the corresponding edges of said bottom plate, and attaching lips on the ends of some of said walls and connected with the adjacent stumps and said walls having said lips being also provided at their upper edges with hooks which overhang the upper parts of the adjacent rails.

6. A sheet metal base for supporting a cushion on a furniture frame having a front rail, a back rail, side rails and front and rear stumps at the corners between said rails, comprising a horizontal bottom plate, vertical front, back and side walls projecting upwardly from the corresponding edges of said bottom plate, and attaching lips on the ends of some of said walls and connected with the adjacent stumps and said walls having said lips being also provided at their upper edges with hooks which overhang the upper parts of the adjacent rails and the other walls being spaced from the adjacent rails and provided at their upper edges with hooks forming reinforcements therefor.
